(57) **CLAIM**

The ornamental design for throwing axe assembly, as shown and described.

DESCRIPTION

FIG. 1 is a top plan view of a throwing axe assembly, showing the new design;

FIG. 2 is a bottom plan view thereof;

FIG. 3 is a rear elevation view thereof;

FIG. 4 is a front elevation view thereof;

FIG. 5 is a left side elevation view thereof;

FIG. 6 is an isometric view showing the bottom and rear thereof;

FIG. 7 is an isometric view showing the top, left and rear thereof; and,

FIG. 8 is an isometric view showing the bottom and front. The broken lines depict portions of the throwing axe assembly in which the design is embodied that are not considered part of the claimed design.
